CLAIM

The ornamental design for a cutting tool, as shown and described.

DESCRIPTION

FIG. 1 is a front, right perspective view of a cutting tool, according to a new design;

FIG. 2 is a top plan view thereof;

FIG. 3 is a front elevational view thereof;

FIG. 4 is a back elevational view thereof;

FIG. 5 is a right elevational view thereof;

FIG. 6 is a left elevational view thereof; and,

FIG. 7 is front elevational view in cross-section of the cutting tool shown in FIG. 1 taken along line 7-7 in FIG. 2. The broken lines on the cutting tool in FIGS. 1 through 7 depict portions of the cutting tool that form no part of the claimed design.

The appearance of any portion of the cutting tool between the break lines shown in FIGS. 1 and 3 through 7 forms no part of the claimed design.

The underside of the cutting tool (i.e., the side of the cutting tools opposite the side shown in FIG. 2) does not form part of the claim design.
